UNITED STATES PATENT OFFICE.

HARRY E. GARRISON, OF WINNEBAGO, ILLINOIS, ASSIGNOR OF ONE-HALF TO ANDREW J. ANDERSON, OF ROCKFORD, ILLINOIS.

APPLIANCE FOR CLOTH-CUTTING MACHINES.

1,293,751.

Specification of Letters Patent. Patented Feb. 11, 1919.

Application filed April 21, 1917. Serial No. 163,678.

To all whom it may concern:

Be it known that I, HARRY E. GARRISON, a citizen of the United States, residing at Winnebago, in the county of Winnebago and 5 State of Illinois, have invented certain new and useful Improvements in Appliances for Cloth-Cutting Machines, of which the following is a specification.

This invention relates in general to cloth cutting machines of the type having a reciprocable cutting knife, and pertains more particularly to an appliance especially designed for protecting the standard and knife guard of these machines and for other purposes mentioned hereinafter.

Such cloth cutting machines are characterized by the provision of a flat base carrying a narrow upright standard which in turn carries a motor and other operating 10 parts including a reciprocable cutting knife operated by the motor and slidably in a slotway in the standard. During the cutting operation, the fabric or material in layers of various thickness is cut vertically by the 15 reciprocating knife, the tapered sides of the standard engaging the parted portions of the fabric and tending to slightly spread the same. And, due to the high speed of the 20 knife and the nature of the work, it is necessary to frequently sharpen the knife so that 25 quick and accurate cutting may be performed. It is the practice to sharpen the knife without removing it from the machine, by employing an abrasive element in the 30 form of an emery or carborundum stick, the operator standing in front of the machine, and making forward and downward strokes 35 on each side of the knife. During this sharpening operation, the emery stick engages the side of the standard and in a comparatively short time the standard becomes 40 roughened and worn, thus impairing the cutting operation and in the course of usage causes the standard to become so worn that 45 it must be replaced by a new one.

In the present instance, I have aimed, primarily, to obviate these objections ensuing from the sharpening operation, by the provision of a new and useful appliance of 50 simple and inexpensive construction, which will preclude any destroying effect upon the standard and will enable the knife to be sharpened at a more proper and accurate cutting angle.

55 To this end, I have provided a metallic guard shaped and especially adapted to en-

gage and sheath both sides of the standard throughout a substantial length thereof, leaving the knife edge exposed so that the guard completely protects the standard 60 against even the slightest effect of the sharpening or abrasive element, and in addition constitutes a guide for determining the proper angle of the sharpening element. I have preferably embodied this guard in the 65 form of spring pressed jaws properly shaped so that they may be quickly positioned and adjusted on a standard and removed therefrom at will without the use of auxiliary fastening means.

70 The construction and operation of my improvements and attendant advantages thereof will be readily appreciated by those skilled in the art as the invention becomes better understood by reference to the following description when considered in connection with the accompanying drawings, in which—

Figure 1 is a side elevation of a cloth-cutting machine of the type to which my invention relates (certain details of the machine being omitted), showing in dotted lines the application of my improved appliance thereto;

Fig. 2 is an enlarged plan sectional view 85 taken on the line 2—2 of Fig. 1, showing my improved appliance attached to the machine standard; and

Fig. 3 is a perspective view of an appliance embodying my improvements.

90 My new and useful appliance is well adapted for use with any cloth-cutting machine of the vertical knife type, that is, in which a vertically reciprocating cutting knife is employed. For purpose of illustration I have shown briefly in the drawings a conventional form of such a cloth-cutting machine, which as will be noted by reference to Fig. 1, includes a flat base 4 to which is centrally and rigidly secured a narrow upright standard 5 upon which is mounted a motor 6 adapted to reciprocate, through the agency of the pitman 7 and knife rod 8, a cutting knife 9 which is guided at its rear edge in a slotway 11 in the standard 5. In 105 use, the machine rests on a cutting table and the operator grasping the handle 12 moves or slides the machine about upon the table so as to cut a lay of fabric or any material disposed between the base 4 and knife guard 110 13 according to any shape or design desired, it being understood that the knife is recip-

located at a very high speed during the cutting operation. It will be noted that the standard which of necessity must be comparatively narrow in order not to spread the 5 parted portions of the cloth too much, is the sole means of support for the motor and operating parts, and therefore, rigidity of the standard is essential.

Because of the frequent need for sharpening the knife it is found most practical to employ an emery or carborundum stick (such as indicated diagrammatically by reference character 15 in Fig. 2) as the abrasive element or tool. During the sharpening operation in which the operator stands in front of the machine and moves the emery stick in downward and forward strokes along the sides of the knife, the tool also bears against the sides of the standard, this being 15 inevitable, because the tool must engage the knife at the proper angle. The wearing effect of the tool upon the standard soon so roughens the same as to impede the standard in its passage between the fabric, so that 20 25 the cutting machine cannot be operated with the ease and facility that it should. Furthermore, during a comparatively short time with regard to the life of a machine of this character the standard will become so worn 30 and cut away at its front and side edges as to render it an unstable means of support, consequently requiring the substitution of a new standard.

By means of the improvements which my 35 invention provides, the effects following from the frequent sharpening of the cutting blade as mentioned are entirely avoided, and in addition, several distinct advantages are gained. My improvement consists in 40 providing a guard or protective sheath adapted to be detachably secured to the standard so as to fully cover the sides of the same while exposing the blade for sharpening. Thus the cutting knife may be 45 sharpened and there will be no destructive wear upon the standard as the same is wholly protected by the guard or sheath. This guard in addition to serving as a protective means, also forms a guide for the 50 sharpening element in that by bearing the element against the guard the element will engage the knife at the proper angle so as to insure an even, accurate cutting edge. By thus protecting the standard, the sides 55 thereof will soon acquire a smooth and highly polished surface by contact with the fabric during the cutting operation, and as a consequence, the cutting machine may be moved through the lays with increasing ease 60 and facility and with greater accuracy and less effort on the part of the operator.

In furtherance of the foregoing, I have provided in the present instance an appli-

ance designated generally by reference character 16 consisting of a pair of pivoted jaws 65 17 shaped to fittingly engage the tapered sides of the standard, as shown plainly in Fig. 2, leaving the forward portion of the knife 9 exposed. The jaws may be formed of any suitable thin material, although it 70 is preferred to form them of case hardened steel so as to add to their longevity. As shown in Figs. 2 and 3, the jaws are shaped to cover the standard throughout substantially its entire length so that the standard 75 will be fully protected against the effect of the sharpening tool. In the present construction, the jaws are pivotally secured together by means of a pin 18, and a suitable coil spring 19 serves to urge the jaws together into holding engagement with the standard. Thus, means is provided for detachably securing the guard to the standard, and it will be obvious that the guard may be quickly and easily positioned and adjusted upon the standard and removed therefrom at will. Also, when the guard is not in use it may be clamped onto the emery stick so as not to become misplaced or lost. It will be noted viewing Fig. 2, that the 80 sharpening tool bears against one of the jaws which serves as a guide to determine the proper angle of the tool relatively to the cutting knife. The rear ends of the jaws are extended so as to form, as it were, wing portions 21 in the general plane of the jaws, to further aid in guiding the 85 sharpening tool.

By the use of this appliance, it will be manifest that the standard of a cloth-cutting machine will be preserved and protected and the operation of the machine will be improved as mentioned above and that a guide is provided for enabling manipulation of the sharpening tool to obtain an even, 90 accurate and proper cutting edge.

I claim:

Means for facilitating the sharpening of the knife of a cloth cutting machine without dismounting said knife, comprising a 100 standard bearing means for supporting the knife while being sharpened, said standard being formed to interfit with said knife to laterally brace the knife in the sharpening operation, means independent of the 105 knife-supporting and bracing means adapted to overlie the side face of the standard to provide a covering shield therefor while exposing the edge of the knife for sharpening, and means for removably securing the 110 shielding means in place during said sharpening, said last mentioned means being separable from the standard and the knife without releasing the latter from operative relation to its supporting and bracing means. 115 120 125

HARRY E. GARRISON.
